US0D1057205S

(12) **United States Design Patent** (10) Patent No.: **US D1,057,205 S**
(45) Date of Patent: ** Jan. 7, 2025

(54) **CONNECTOR**

(71) Applicant: **Ryan Dutchak**, Nelson (CA)

(72) Inventor: **Ryan Dutchak**, Nelson (CA)

(**) Term: **15 Years**

(21) Appl. No.: **29/791,827**

(22) Filed: **Feb. 10, 2022**

(51) LOC (15) Cl. **25-01**

(52) U.S. Cl.

USPC **D25/133**

(58) **Field of Classification Search**

USPC D25/61, 113, 133; D8/349, 354, 382,
D8/399

CPC .. E04B 1/40; E04B 1/3211; E04B 2001/3247;
E04B 1/1903; A01G 9/1407

See application file for complete search history.
